UNITED STATES PATENT OFFICE.

CHARLES A. JENSEN, OF BAILEY, NEBRASKA.

TRUSS.

No. 908,998.

Specification of Letters Patent.

Patented Jan. 5, 1909.

Application filed March 14, 1908. Serial No. 421,194.

To all whom it may concern:

Be it known that I, CHARLES A. JENSEN, a citizen of the United States, residing at Bailey, in the county of Cherry, State of Nebraska, have invented certain new and useful Improvements in Trusses; and I do hereby declare the following to be a full, clear, and exact description of the invention, such as will enable others skilled in the art 10 to which it appertains to make and use the same.

This invention relates to certain new and useful improvements in trusses.

The object of my invention is to provide a 15 truss so constructed that the pressure of the pad may be regulated by the operator without disrobing as the construction permits the pad to be adjusted through the clothing.

A further object of my invention is to provide 20 a truss so constructed that the pad may be reversed permitting the truss to be adjusted to the right or left side as will be described more fully hereinafter.

In the accompanying drawings, I have 25 shown in Figure 1 a truss constructed according to my invention showing the pad adjusted to be carried upon the left side. Fig. 2 shows a side view with portions removed of the pad. Fig. 3 shows a top view of the 30 spring plate as used in my invention. Fig. 4 shows the pad as arranged when used on the right side. Fig. 5 shows an edge view of the pad disclosing the securing ears as 35 opened, and Fig. 6 shows a top view of the spring as used in connection with my invention.

Referring by letter to the drawing A shows an ordinary body belt provided at one end with the plate 2 having a series of key- 40 slots comprising the eyes 3 and slots 4. At the opposite end this belt is provided with a stem 5 having the flattened portion 6 by means of which this stem is secured to the spring 8, this spring being held within the 45 belt A and exerts a gentle pressure upon the abdomen of the wearer.

Approximately midlength the stem 5 is provided with a segment ratchet 10, this ratchet being semi-circular in cross section 50 as shown in Fig. 2 and is provided with two sets of ratchet teeth, one set of teeth being inclined in one direction and the remaining teeth in opposite direction. It will be noticed that the circumference of the ratchet 55 wheel is equally divided so as to provide the two sets of teeth *a* and *b* as shown in Fig. 2.

This stem 5 by means of which the belt is secured to the body of the wearer is provided at its end with a narrow neck portion 12 adapted to fit into the slot 4 and the enlarged head 13 being adapted to work through the eye 3 so that the stem may be secured to the plate 2.

In connection with the belt I use a pad 14 as is usual in truss construction. My pad 65 comprises a plate 14 provided with the re-curved perforated spaced spring ears 15 which ears are adapted to engage the stem 5, the ears being located upon opposite sides of the ratchet 10, as shown in Fig. 1. The 70 plate 14 is perforated as shown at *u* in Fig. 5 while each ear is provided with a perforation *v* and passing through the perforation *v* and threading into the opening *u* is a screw 17. The ears 15 are sufficiently resilient so that 75 they may be sprung over the stem 5. After the ears have been carried over the stem 5 they are secured by means of the screws 17 in such a manner that on the removal of the screws the ears may be bent upward permitting 80 the detaching and reversing of the pad.

Secured to the pad plate 14 by means of the screws 22 is an ear provided spring plate 20 having the upstanding ears 23 and the screw openings 24 through which the screws 85 22 pass in securing this spring plate to the pad plate 14. The lower end of this plate 20 is bent outward and forms a spring against which the lower end of the pawl 27 rests, this pawl at its upper end being in engagement 90 with the ratchet 10.

In Fig. 1 the body belt A is shown with the pad 14 adjusted to press against the left side of the wearer. If it were desired that this pad should be arranged to exert a pressure 95 upon the right side, the screws 17 are removed when the pad is detached from the stem, the belt is reversed, when the pad is again secured so that said pad will rest upon the right side of the wearer. In Fig. 4, the 100 pad is shown in this reversed position. By means of the key slots, the body belt is given suitable adjustment.

Having thus described my said invention, what I claim as new and desire to secure by 105 U. S. Letters Patent is—

A truss having in combination, a body belt, a plate having key slots secured to one end of said belt, a hook-ended stem secured to the remaining end of said belt adapted to 110 engage, within said key slots, a segmental ratchet secured to said stem having half its

circumference provided with teeth inclined in one direction, the teeth of the remaining circumference being inclined in opposite direction, a pad, two spaced spring ears secured to said pad, said ears being removably held upon said stem upon opposite sides of said ratchet, a spring plate having two up-standing ears, the end of said plate being bent outward to form a spring, and a pawl carried by said ears one end engaging one set

of said teeth the remaining end being engaged by said spring, all arranged as and for the purpose set forth.

In testimony whereof, I affix my signature, in presence of two witnesses.

CHARLES A. JENSEN.
